UNITED STATES PATENT OFFICE.

CHARLES SANDFORD, SR., OF MADOC, ONTARIO, CANADA, ASSIGNOR OF ONE-HALF TO
CHRISTOPHER HENDERSON, OF MADOC, ONTARIO, CANADA.

LOCK.

1,250,027.

Specification of Letters Patent. Patented Dec. 11, 1917.

Application filed May 31, 1917. Serial No. 172,023.

To all whom it may concern:

Be it known that I, CHARLES SANDFORD, Sr., of the town of Madoc, in the county of Hastings, in the Province of Ontario, Canada, have invented certain new and useful Improvements in Locks, of which the following is the specification.

My invention relates to improvements in locks and the object of the invention is to 10 devise a simple and cheap form of lock in which all springs are dispensed with and yet which will operate freely and instantaneously and further to provide means whereby by the pull on the handle for opening the 15 door will automatically operate to withdraw the bolt thereof and it consists essentially of the following arrangement and construction of parts as hereinafter more particularly explained.

20 Figure 1, is a perspective view of a door portion showing my lock applied thereto.

Fig. 2, is an enlarged vertical section on line $x-y$ Fig. 1.

25 Fig. 3, is a sectional view on line $x'-y'$ Fig. 2.

Fig. 4, is an enlarged perspective detail of my lock removed from the door with the cover plate of the lock removed.

30 Fig. 5, is a plan section on line x^2-y^2 Fig. 2.

Fig. 6, is a detail elevation of a fragmentary portion of my lock showing the means for locking the bolt in the door locking position.

35 Fig. 7, is a modified form of my lock adapted for use as an automobile lock.

Fig. 8, is a sectional view on line x^3-y^3 Fig. 7.

40 In the drawings like letters of reference indicate corresponding parts in the various figures.

1 indicates a door frame and 2 a door which is hinged at 3 to the door frame. 4 and 5 indicate escutcheon plates, which are 45 secured to each face of the door 2 by screws 6 and 7. 8 indicates my lock, which is fitted into the mortise 8^x.

9 and 10 indicate alined slots formed in the door so as to extend into the upper portion 50 of the mortise 8^x.

11 and 12 indicate slots formed in the escutcheon plates 4 and 5 in alinement with the slots 9 and 10. 13 and 14 indicate projections extending outwardly from each escutcheon plate 4 and 5, such projections be-

ing provided with segmental circular upper portions 13^x and 14^x.

15 and 16 indicate lever members provided with segmental circular recesses 15^x and 16^x, which fit upon the segmental circular portions 13^x and 14^x, each arc 15^x and 16^x being shorter than the corresponding arc 13^x and 14^x so as to allow of the free tilting movement of the lever arm 15 and 16 in a vertical plane, the projections 13^x and 14^x forming the fulcrum on which the levers swing. 17 and 18 indicate lugs which are substantially U-shaped in cross section. 19 and 20 indicate handles provided with lug portions 21 and 22 fitting into the U-shaped lugs 17 and 18. The lugs 21 and 22 are provided with orifices 23 in alinement with the orifices 24 formed in the side portions of the U-shaped lugs 17 and 18.

25 indicates pins and bolts extending through such alined orifices whereby the handles 19 and 20 are swingably connected to the lugs 17 and 18. The lower portion of each handle 19 and 20 is provided with a depending portion 26 in alinement with its outer edge and a depending portion 27, which is segmental circular in form in proximity to its inner edge and an interposed recess 28 intervening between the projecting portions 26 and 27. Each lever 15 and 16 is provided with an upwardly projecting hook-shaped portion 29 fitting into a corresponding recess 28 and a recess 29^x into which the projection 27 fits.

It will thus be seen that when the handle 19 or 20 is pulled upon it is drawn into the dotted position shown in Fig. 2, the projection 27 engaging with the recess 29^x and tilting the lever 15 or 16 upwardly into the dotted position swinging it around the projection 13^x or 14^x as the case may be. By the raising of the lever 15 or 16 into the inclined position my lock is operated.

I will now describe the construction of my lock 8.

8^x indicates the casing of my lock 8, the face plates of which are provided with key orifices 30 and the outer face plate with a key orifice 31. 32 indicates a swingable member supported upon the cross pin 33 carried by one face plate of the casing 8. The member 32 is provided with a normally horizontally extending portion 34 which rests upon the upper edges of the levers 15 and 16, the upper face of the projecting por-

tion 34 being inclined downwardly as indicated in Fig. 4 so as to permit of the upward swing of such member against the upper wall of the casing 8*. The member 32 is provided with a depending portion 35 having a slightly hooked end 36. 37 indicates a latch bolt orifice of the casing. 38 indicates my latch bolt, which is provided with recesses 39 and 40. The rear or inner 10 end of the latch bolt 38 is tapered at 41 as indicated, the recess 40 being located in such tapered portion.

In the drawings I have shown both the upper and lower edge of the bolt provided 15 with recesses 39 and 40 so that the latch bolt may be made reversible to the right or left hand.

42 and 43 indicate flanges formed in the interior of the casing 8*, the flange 42 being 20 slightly inclined upwardly from the outer wall of the casing and the flange 43 inclined upwardly substantially parallel to the tapered portion 41 of the latch bolt 38. 44 indicates a ball held in the recess 39 upon the 25 flange 42. 45 indicates a ball held in the recess 40 upon the flange 43.

When the handle 19 or 20 of the door is pulled as above described and one of the levers 15 or 16 is thrown into the tilted 30 position indicated by dotted lines in Fig. 2 the member 32 is raised by such tilted lever into the dotted position shown in Fig. 4 thereby drawing the latch bolt 38 into the dotted position by means of the engaging 35 hook 35 engaging the upper recess 40. When the handle of the door is released the parts assume their normal position by means of gravity, the balls 44 and 45 rolling down the inclined flanges 43 and 42 from the 40 dotted position shown in this figure back to their normal or full position and thereby carrying the latch bolt 38 so as to project through the orifice 37 to latch the door.

In order to provide a latch lock for the 45 door the ratchet shaped recess 46 is formed in the upper edge of the latch bolt 38. 47 indicates the handle of the latch lock, such handle being provided with a rectangular tongue portion 48 extending inwardly into 50 the casing of the lock. 49 indicates a cylindrical slotted rocking member turnably held in circular orifices 50 formed in the face plates of the lock casing 8* and into which the tongue 48 extends. 51 indicates a ratchet 55 shaped tooth extending outwardly from such cylindrical portion toward the key orifice 31. 52 indicates an arm extending outwardly from such rocking member and normally resting upon the upper edge of the latch lock 46. The lower face of the arm 52 is provided with a ratchet-shaped projection 53, which fits in its locking position into the ratchet recess 46.

When it is desired to free the latch from

the inside of the door all that it is necessary to do is to turn the handle 47 to raise the arm 52 into the dotted position.

When it is desired to unfasten the latch lock from the outside of the door a suitable key is inserted through the key orifice 31, the 70 bit of the key being of such length as to engage the projection 51 as the key is turned in the direction indicated by arrow (see Fig. 4). By this means the arm 52 is raised into the dotted position before described so as to 75 free the projection 53 from the notch 46 thereby allowing the latch bolt to be withdrawn.

In order to permanently lock the latch lock in position so that it can be released by 80 key operated means only, I have provided the following mechanism.

54 indicates a rib extending across the lower wall 55 of the casing 8* in proximity to the key orifice 30. 56 indicates a flange 85 extending outwardly from one of the side plates of the lock casing 8* and set at an incline. 57 indicates a locking member comprising a plate portion 58 fitting against the inner face of one of the face plates of the 90 lock and provided in its lower edge with a recess 59. 60 indicates a head which is formed integral with the lower portion of the plate 58 and normally fits between the inclined flange 56 and rib 54. 61 indicates 95 a cross groove formed in the lower face of the head in proximity to the cross rib 54.

62 and 63 indicate projections, which form the wards of the lock co-acting with the key. When the key is inserted through the key 100 orifice 30 and turned in the direction of arrow the outer edge of the bit of the key engages with the upper portion of the recess 59 thereby giving an upward and rearward lift to the plate 58 carrying the upper portion thereof into such a position as to be inserted between the rear end of the latch lock and the opposing wall of the casing.

It will be noticed particularly on referring to Fig. 5 that the rear edge of the plate 110 portion 58 is slightly arc-shaped thereby permitting the lower end or head 60 to be carried upwardly and swung rearwardly so that the cross groove 61 engages with the rib 54 as shown in Fig. 5. By turning the key in the opposite direction the key first engages with the upper portion of the recess 59 lifting the plates 58 so that the cross groove 61 is carried clear of the rib 54. As the key is swung in the opposite direction 115 to the arrow it engages the edge of the recess in proximity to the point X carrying the plate 58 in the direction of the arrow (see Fig. 5) so that the head 60 is carried back to its normal position between the 120 flange 56 and rib 54.

In order to further lock the plate 58 in position the member 62* is swingably car-

ried by such plate, such member being provided with an annular portion 63 swung upon a pin 64 extending outwardly from the plate 58. The lower edge of the member 62 is provided with a curved recess portion 66 with which the key inserted in the slot 30 also engages when it is turned in the opposite direction to the arrow so as to carry the plate 58 from its locking position.

10 After the plate 58 has been raised during the unlocking operation as above described the key engages the recess 66 swinging the locking member 62 upwardly clear of the flange 56 thereby permitting of the free 15 return movement of the head 60. When the plate 58 is carried to the locking position the member 62 drops into the position shown in Fig. 5 so that the free end thereof engages with the end edge 56 locking the 20 parts in position.

Referring to Figs. 7 and 8. 70 indicates the casing of the lock provided with the usual face plate in which is located a bolt orifice. 72 indicates an inclined way 25 formed in the bottom of the casing 70. 73 indicates a slot formed in one side wall of the casing and 74 indicates a lug extending upwardly from the casing and provided with a bearing orifice 75. 76 indicates 30 a substantially triangular shaped weight member having inclined faces 77 and 78 set at different levels and a downward projection 79. 80 indicates a bolt member provided at its upper edge with an inclined 35 face 81 opposing the inclined face 78 and an inclined face 82, which opposes the lower portion of the inclined face 78 below the projection 79 and the upper portion of the inclined face 77.

40 83 indicates a projection extending upwardly from the inner end of the bolt member, the upper portion being reduced so as to enter a recess in the weight member 76 indicated by dotted line 84. 85 indicates an 45 upwardly extending projection also extending from the bolt member and normally in proximity to the face plate 71. The upper end of the projection 85 is designed to enter into a recess in the weight member 76 indicated by dotted line 87 when the bolt is withdrawn.

88 and 89 indicate arc-shaped recesses formed in the lower end of the bolt member and 90 indicates a ball fitting into the recess 88 and resting upon the bottom of the lock casing 70. 91 indicates a ball fitting into the recess 89 and resting upon the in-

clined way 72 and 92 indicates a ball fitting between the inclined faces 78 and 81 and 93 indicates a ball fitting between the inclined 60 faces 77 and 82. 94 indicates the operating lever provided with a pin 95 journaled in the orifice 75 and a pin 96 extending through the slot 73 into an orifice 97 formed in the lock member 80. 98 indicates the 65 handle of the operating lever.

When it is desired to operate the lock all that it is necessary to do is to raise the handle 98 thereby swinging the operating lever so as to carry the pin 96 rearwardly 70 thereby carrying the bolt member 80 in the same direction withdrawing the bolt. During this movement the ball 90 rolls upon the lower wall of the casing and the ball 91 up the incline 72. Simultaneously the balls 92 75 and 93 roll between the opposing faces 81 and 78 and 82 and 77 into the position shown by dotted lines in Fig. 7 raising the weight member 76 to the dotted position. As soon as the handle 98 is released the 80 weight member carried by the bolt member serves to force the bolt back to its normal or locked position or the position shown in full lines in the drawings.

From this description it will be seen that 85 I have devised a lock which entirely operates by gravity, the latch bolt thereof being carried by ball bearings allowing the free return movement of the latch lock to the locking position after the handle is released, 90 and in which simple latch locking means are provided for whereby the latch lock may be temporarily locked in position so as to be easily opened from the inside of a door and also means whereby the lock may 95 be permanently locked in position so that it can only be opened by key operated means from either side of the door.

What I claim as my invention is.

In a lock, the combination with the lock 100 casing having the latch bolt orifice, of a latch bolt, flanges inclined to the plane of movement of the bolt supported within the casing, balls interposed between the lower edge of the latch bolt and the inclined 105 flanges, and means operated from the exterior of the latch casing for withdrawing the bolt in slidable engagement with the balls.

CHARLES SANDFORD.
